UNITED STATES PATENT OFFICE.

JOHN F. NEWSOM, OF SAN FRANCISCO, CALIFORNIA.

TORPEDO-GUARD.

1,293,169.

Specification of Letters Patent.

Patented Feb. 4, 1919.

Application filed July 5, 1917. Serial No. 178,638.

To all whom it may concern:

Be it known that I, JOHN F. NEWSOM, a citizen of the United States, residing at the city and county of San Francisco and State of California, have invented new and useful Improvements in Torpedo-Guards, of which the following is a specification.

This invention relates to a torpedo guard for vessels that is positioned a suitable distance from the hull of a vessel when it is in the danger zone, and that is nested adjacent the hull of the vessel when it is outside of the danger zone.

The invention consists of the parts and the construction and combination of parts as hereinafter more fully described and claimed, having reference to the accompanying drawings, in which

Fig. 1 is an end elevation in section of one side of a vessel showing the application of the invention.

Fig. 2 is a similar view showing the guard nested against the side of the vessel.

Fig. 3 is a cross section on line 3—3 of Fig. 1.

Fig. 4 is a plan view partly in section of the inner pivotally mounted end of the arm.

Fig. 5 is a plan section of one side of the vessel showing the guards in nested position.

Fig. 6 is an end view similar to Fig. 1 showing a modification of the structure employed.

Fig. 7 is a view similar to Fig. 2 showing the guard in nested position.

Fig. 8 is a detail sectional view of the inner end of the arm showing the worm gear drive.

Fig. 9 is a side elevation of the traveling head.

Referring to the drawings in detail A indicates in general, the deck of a vessel, and 2 one of the sides. Pivotally secured, as at 3, in a bearing bracket 4 permanently secured 45 to the side of the vessel is a boom or arm 5. There are a suitable number of arms 5 arranged along each side of the vessel and the arms are arranged in pairs, each pair being

arranged to support or carry a guard member generally indicated at B. Referring to Fig. 4, it will be seen that each arm is carried in bearing bushings 6, and that extending through each pair of bearing bushings is a shaft 7 upon which is secured a worm gear 8. By referring to the same figure, and also to Fig. 3, it will be seen that each arm is hollow and approximately rectangular in cross-section to form a guide for a traveling head 9. Journaled in each arm and extending through each traveling head is a screw-shaft 10 on the inner end of which is secured a worm wheel 11. This worm wheel remains in constant mesh with the worm gear 3, and when turned by same serves as a means for moving the traveling head in and out on the guides formed in the arm, as will herein-after be described.

Arranged on one side of each bearing bracket 4 and journaled in bearings is a shaft 12, which extends up to the deck of the vessel. This shaft may be provided with a hand-wheel or may be turned by any other suitable means.

Secured on the lower end of said shaft is bevel gear 13, and inter-meshing with said gear is a second bevel gear 14 which is secured on the outer end of shaft 7; the shaft 12 and the gears 13—14 serving as means for turning the screw-shaft 10. Permanently secured along the bilge line of the vessel is a trough-shaped supporting shelf 15, which is adapted to support the guards when they are nested against the side of the vessel, as shown in Figs. 2 and 5, and connected with the lower end of each guard for the purpose of swinging it inwardly into the trough is a cable 16. There are a pair of these cables, one being secured to each end of the guard as shown at 17. Each cable passes from the point of attachment shown, over a shive 18 and passes from this point up to a winding drum, or other tackle, carried on deck. The cable 16 assumes the dotted line position shown at 16^a when the guards are to be swung inwardly, but under normal conditions assumes the full line posi-

tion shown at 16 when the guards are hanging in guarding position. This is accomplished by securing a pair of shives 19 and 20 to each arm 5. A cable 21 operated from the deck of the vessel, and carrying the floating block 22 permits the cable 16 to be pulled up into alinement with the arms 5. This is accomplished by passing the cable 21 through the floating block 22, and then over the shives 20 and 19. The end of the cable 21 carries a loop 23 through which the cable 16 passes, and then through a loop 24 carried by the floating block. It is therefore possible to raise the cable 16 or lower the same by means of the cable 21.

Each guard employed consists of a hollow caisson which is pivotally supported as at 24 between a pair of traveling heads 9. The caissons may be constructed of steel or other suitable material, and the main plates forming same are spaced apart a sufficient distance to form a comparatively large chamber. Each caisson may therefore be provided with loading openings 25, or manholes, at the top, which are water tight and the chambers formed in the guards can in this manner be loaded with grain, or other freight.

Secured to the outer end of each arm 5 is a cable 26. Each cable passes upwardly to the winding drum of a winch 54 carried by the ship and this drum is preferably constructed so that a certain freedom of movement about its driving shaft is permitted; this winch being more particularly described in my co-pending application entitled Torpedo and mine guard for vessels, filed July 5th, 1917, Serial No. 178,637. In this manner a resilient movement between each arm and the supporting cables, or the winch to which they are attached, is permitted. This is of great importance when the ship is at sea, particularly during rough weather as the sea encountered and the rolling of the ship necessitates a certain freedom of movement of the supporting arms. A structure too rigid would under such conditions break or be carried away while the resilient mounting here shown takes care of such stresses, thereby saving the supporting structure against destruction.

In operation with the guards lowered into guarding position as shown in Fig. 1, if it is desired to raise and nest the same against the vessel's side, it is first necessary to pay out on the cables 21 to permit the main cable 16 to be lowered into the position shown at 16^a. The winch carrying the cables 26 may then be started to partly raise the arms 5 about their inner pivotal connections 3 and a pull may also be exerted on the cable 16 to gradually swing the lower end of each caisson inwardly against the supporting shelf 15. The traveling heads 9

may also be moved inwardly by the screw-shafts 10 through power transmitted from shafts 12 and comparatively small movement is imparted to the arms 5 as it is really only necessary to raise the same sufficiently to permit the lower ends of the guards to swing inwardly above the outer ledge of the supporting shelf 15. A continued movement may then be imparted through the screw-shafts 10 until the traveling heads reach their innermost positions. Each guard will during said movement drop into the trough or shelf 15 and the arms may in this position be swung completely up against the side of the vessel as shown in Fig. 2.

The several movements described take place partly in unison and partly independent of each other.

By referring to Fig. 5 it will be seen that a horizontal cross-section of a guard member shows a stream-line shape. This is necessary to reduce resistance to the smallest degree possible when the guards are extended to guarding position, and it is also of advantage when the guards are nested against the side of the vessel, as shown in Fig. 5. The spaces indicated at 30 between each guard section when nested are preferably covered with a filling plate 31 having an exterior contour conforming to the stream-line shape of the guards, in this manner preventing water from entering between the guards and exerting a destructive action when in a heavy sea. Practically a smooth exterior similar to the side of the vessel is presented when the guards are nested, and as each guard may serve as a freight carrier, it can readily be seen that the freighting capacity of the vessel is rather increased while change in the speed of the vessel will hardly be noticed.

The provision of the traveling heads 9 and the position of the supporting shelf 15 is another important feature as it permits each guard member to be nested snugly against the side of the vessel without raising the same appreciably above the water level.

A modification of the structure shown in Figs. 1 and 2 is shown in Figs. 6 and 7. The arms 5 employed, are in this instance constructed of two telescoping sections 40 and 41. The outer section serves as a nut and is extended or retracted by a gearing mechanism generally indicated at 42, practically identical to the mechanism shown in Figs. 1 and 2. The arm section 41 really serves the function of the traveling head 9 previously described, but its movement is limited. That is, it cannot possibly be retracted to a position as close to the pivotal connection of the arm as the other structure shown. The movement of the guard from extended guarding position to the nested position shown in Fig. 7 therefore necessitates lifting each

guard a comparatively greater distance and higher out of the water to place it in the supporting shelf shown. By referring to the guard shown in Figs 6 and 7 it will be

- 5 seen that the lower part of the chamber formed is filled with concrete or other ballasting material, which can be permanently secured therein. This ballasting material is placed therein for the purpose of counter-
 10 acting any downward thrust or tilting action imparted while the guards are submerged; the ballast being heavier in the rear end than in the front of the guard tends to counterbalance or offset any tilting thrust im-
 15 parted.

The guard shown in Figs. 6 and 7 when raised is preferably swung in an inward direction by means of a pair of cables 50. These cables are attached to each end of
 20 the caisson, as shown at 51. The cables then pass over shives 52 then up over a pair of shives 53 and from this point pass over a drum carried by the winch 54. A pull exerted on the cables 26 and 50 causes the
 25 arms to be raised, and also the lower end of the caisson to be swung inward into a position where it may be dropped directly into the trough-shaped supporting shelf; both sets of cables being relied on to lift
 30 the caisson, and the arms when it is swung into nesting position.

The cables 50 may also be attached to the preferred form of the structure shown in the remaining figures of the drawings, but
 35 it is in this instance only illustrated in connection with the modification.

Having thus described my invention what I claim and desire to secure by Letters Patent is—

- 40 1. A torpedo guard comprising a guard member, means on a vessel for raising and lowering said guard member and a supporting shelf comprising a trough secured to the vessel adapted to engage a portion of the
 45 guard member and means for forcing the engaging portion of said guard member into said trough and holding the same therein.

2. A torpedo guard comprising a guard member, means on a vessel for raising and lowering said guard member, a supporting shelf secured to the vessel having a trough formed therein adapted to engage the lower end of the guard member and support the same and means engaging the guard member to hold the same positively against displacement from said trough.

3. A torpedo guard comprising a pair of arms pivotally mounted on a vessel's side, a screw shaft journaled in each arm, a guide on each arm, a traveling head slidably mounted in each guide through which the screw shafts pass, means for revolving said shafts to move the traveling heads in and out on the arms, and a guard member car-

ried by and pivotally mounted between the traveling heads.

4. A torpedo guard comprising a pair of arms pivotally mounted on a vessel's side, a screw shaft journaled in each arm, a guide on each arm, a traveling head slidably mounted in each guide through which the screw shafts pass, means for revolving said shafts to move the traveling heads in and out on the arms, a guard member carried by and pivotally mounted between the traveling heads, a trough shaped supporting shelf secured to the side of the vessel, means for raising the arms up against the side of the vessel, to raise the guard up into the trough, and means attached to the lower end of the guard to swing the end into the trough while it is being raised.

5. A torpedo guard comprising a pair of arms pivotally mounted on a vessel's side, a screw shaft journaled in each arm, a guide on each arm, a traveling head slidably mounted in each guide through which the screw shafts pass, a shaft extending through each pivot connection, a pair of intermeshing worm gears connecting said shafts and the screw shafts, a shaft journaled on the vessel's side provided with means for turning same, gears connecting said shafts with the shaft passing through the pivot connections to permit turning movement to be transmitted to the screw shafts, a guard member carried by and pivotally mounted between the traveling heads, means for raising and lowering the arms in unison to swing the guards into guarding position, or against the vessel's side, a trough shaped supporting shelf adapted to receive the lower end of the guard when swung in against the side, and means for securing the guard against removal from the trough.

6. A torpedo guard comprising a pair of arms pivotally mounted on a vessel's side, a screw shaft journaled in each arm, a guide on each arm, a traveling head slidably mounted in each guide through which the screw shafts pass, a shaft extending through each pivot connection, a pair of intermeshing worm gears connecting said shafts and the screw shafts, a shaft journaled on the vessel's side provided with means for turning same, gears connecting said shafts with the shaft passing through the pivot connections to permit turning movement to be transmitted to the screw shafts, a guard member carried by and pivotally mounted between the traveling heads, means for raising and lowering the arms in unison to swing the guards into guarding position, or against the vessel's side, a trough shaped supporting shelf adapted to receive the lower end of the guard when swung in against the side, and means for securing the guard against removal from the trough.
